DESIGN FOR A GLOVE

Clara H. Gordon, New York, N. Y., assignor of one-half to Paula Strauss, New York, N. Y.

Application May 16, 1934, Serial No. 51,800

Term of patent 3½ years

To all whom it may concern:

Be it known that I, CLARA H. GORDON, a citizen of the United States, and residing at New York, in the county of New York and State of New York, have invented a new, original, and ornamental Design for a Glove, of which the following is a specification, reference being had to the accompanying drawing, forming part thereof, in which

Fig. 1 is a perspective view of the glove as worn, and

Fig. 2 is a plan view of the glove in flat condition.

The entire body of the glove up to the cuff is made up of the knitted blocks, shown on the drawing.

I claim:

The ornamental design for a glove substantially as shown and described.

CLARA H. GORDON.
